CLAIM

We claim the ornamental design for a snag-free hosiery glove, as shown and described.

DESCRIPTION

FIG. 1 is a perspective view of a snag-free hosiery glove showing our new design;

FIG. 2 is a rear elevational view thereof;

FIG. 3 is a front elevational view thereof;

FIG. 4 is a side elevational view thereof;

FIG. 5 is an elevational view of the opposite side thereof;

FIG. 6 is a top plan view thereof;

FIG. 7 is a bottom plan view thereof; and,

FIG. 8 is a reduced perspective view showing a pair of the snag-free hosiery gloves in use; the broken lines depict environmental structure for illustrative purposes only and form no part of the claimed design.
